UNITED STATES PATENT OFFICE.

JAMES ALEXANDER FLANAGAN, OF TORONTO, ONTARIO, CANADA.

SEWING-MACHINE.

1,387,143.

Specification of Letters Patent.

Patented Aug. 9, 1921.

Original application filed February 4, 1919, Serial No. 274,902. Divided and this application filed February 4, 1920, Serial No. 356,204. Renewed June 1, 1921. Serial No. 474,302.

To all whom it may concern:

Be it known that I, JAMES ALEXANDER FLANAGAN, of the city of Toronto, in the county of York and Province of Ontario, 5 Dominion of Canada, have invented certain new and useful Improvements in Sewing Machines; and I hereby declare that the following is a full, clear, and exact description of the same, this application being a division 10 of my concurrent application No. 274,902, filed February 4th, 1919.

My invention relates to an improvement in sewing machines of the type shown and described in my concurrent application Serial 15 No. 274,902, and the object of the invention is to so design the machine that it may be used either for sewing flat or tubular work, or for darning.

With this object in view, the feed and 20 looper mechanisms are inclosed in a specially designed housing, comprising a spheroidal part and a tubular part constricted with regard to the spheroidal part the top of which forms a throat plate for the feed dog.

25 The bed of the machine is constructed with an opening of relatively considerable width for access to the housing when the machine is to be used for darning or for sewing tubular work, and this opening is provided 30 with two removable cover slides, which together with the throat plate close the opening, when the machine is to be used for sewing flat work.

For an understanding of the invention 35 reference is to be had to the following description and to the accompanying drawings in which:

Figure 1, is a vertical sectional view of a fragment of a sewing machine,

40 Fig. 2, is a fragmentary plan view of the cover slides showing in dotted lines the housing for the feed and looper mechanisms.

Fig. 3, is a fragmentary view similar to Fig. 2, showing the cover slides removed.

45 Like characters of reference refer to like parts throughout the specification and drawings.

In the preferred construction of the machine, the horizontal feed shaft *a* is of a tubular character and is journaled in suitable 50 bearings *b*; *b'*, forming part of, or rigidly connected to the frame *b''*, and the horizontal looper shaft *c* extends lengthwise through the feed shaft and projects beyond 55 the ends thereof.

This arrangement brings the feed and looper shafts into co-axial relation and permits of the feed and looper mechanisms being centralized with regard to each other, and to the opening *i''* in the bed *i'* of the 60 machine. This opening *i''* is of relatively considerable width for the purpose herein-after set forth, and is normally closed, when the machine is used for sewing flat work, by two removable cover slides *i*, *i'*. 65

Fixed on the ends of the feed shaft *a* are caps *d*, *d'*, constituting the bearings for the looper shaft *c*, and fixed on the looper shaft in front of and adjacent to the bearing *d*, is the feed cam *e* imparting vertical reciprocation to the feed dog *f*. The feed dog *f* is provided with a feed bar *f'*, which moves laterally in a guideway on the top surface of a feed slide *e'* and this slide has a central opening in which operates the feed cam *e*. 75

Extending horizontally from the feed bar is a pin *f''*, which enters a slot *d''* in the rocker arm *d''* fixed on the feed shaft.

At or near the rear end of the feed shaft *a* is a feed drive *a'* imparting a rocking movement to the feed shaft, during which the rocker arm causes the lateral reciprocation of the feed dog and feed bar. 80

At the same end of the looper shaft *c*, as the feed drive *a'*, is the drive *c'* for the 85 looper shaft, which imparts rotary movement to the looper shaft and causes the rotation of the feed cam.

During the operation of the drives *a'*, *c'*, the feed shaft *a* is rocked in the bearings 90 *b*, *b'*, and causes the oscillating movement of the rocker arm and the lateral reciprocation of the feed dog concurrently with the rotation of the looper shaft, the feed cam during the rotation of the looper shaft effecting 95 the vertical reciprocation of the feed dog.

Inclosing the feed and looper shafts, beyond the front bearing *b* is the horizontal tubular part *h*, of the housing forming the 100 subject matter of this invention, and at end of the tubular part and inclosing the rocker arm, feed dog, feed bar, feed slide, feed cam, and looper *g'*, which for convenience may be termed the feed and looper mechanisms, 105 is the spheroidal part *h'* of the housing, these parts of the housing being preferably of an integral character, the tubular part being constricted with regard to the spheroidal part as shown in Fig. 1. 110

The top of the spheroidal part h' is flattened or provided with a throat plate h'' , suitably slotted at h^3 for the feed dog f . The frame b'' of the machine is formed 5 with a comparatively wide opening above the housing and this opening is closed by the two removable cover slides i, i' , which when withdrawn from the frame permit of free access to the housing, so that it can 10 then be used as a support for tubular work.

When the cover slides i, i' , are withdrawn from the bed of the frame, tubular work, for instance socks, sleeves, trouser legs or the like, may be drawn over the spheroidal 15 part of the housing, and in the direction of the bearing b , until the spot where the sewing is to be done comes into line with the needle bar of the machine, the throat plate h'' then supporting that part of the surface 20 of the work where the sewing is to be done and the spheroidal part of the housing distending the work during the sewing operation.

The cover slides i, i' , are complementary to 25 the throat plate h'' and when they are in position, they and the top surface of the throat plate h'' are in the same plane. The throat plate h'' is shown to be of a circular shape, and to accommodate it, the adj- 30 cent edges of the cover slides i, i' , are formed with central semi-circular recesses k , each corresponding to one-half of the throat plate h'' , these recesses extending inwardly from 35 these edges of the cover slides i, i' , so that when the cover slides are in their assembled position their edges will abut on the line j .

Various means may be provided for securing the housing in position, a convenient means for this purpose, being to form the 40 inner end of the tubular part h with a circular flange h^4 to abut against the adjacent face of the bearing b , and to fasten this flange to the bearing by means of machine 45 bolts or screws j' .

For access to the interior of the housing, the spheroidal part h' is made with a hinged 50 segment forming a gate l , the chord of which is preferably greater than the diameter of the shuttle holder, so that ample space may be provided for access to the interior of the housing.

Having thus fully described my invention, what I claim as new and desire to secure by Letters Patent is:

1. In a sewing machine, the combination 55 of the feed and looper mechanisms, and a housing therefor comprising a spheroidal part and a horizontally extending tubular part constricted with regard to the spheroidal part and carrying the latter at the end thereof.

2. In a sewing machine, the combination 65 of the feed and looper mechanisms, and a housing therefor comprising a spheroidal part, a horizontally extending tubular part, constricted with regard to the spheroidal part and carrying the latter at the end thereof, and a movable segment for the spheroidal part providing access to the feed and looper mechanisms.

3. In a sewing machine, the combination 75 of the feed and looper mechanisms, and a housing therefor comprising a spheroidal part and a horizontally extending tubular part constricted with regard to the spheroidal part, and carrying the latter at the end thereof, the spheroidal part having in its top surface a throat plate for the feed dog.

4. A sewing machine comprising a bed 80 plate having an opening of relatively considerable width and removable cover slides for the opening, in combination with feed and looper mechanisms below the opening, and a housing therefor comprising a spheroidal part and a tubular part constricted 85 with regard to the spheroidal part.

5. A sewing machine comprising a bed plate having an opening of relatively considerable width and removable cover slides 90 for the opening, in combination with feed and looper mechanisms below the opening, and a housing therefor comprising a spheroidal part and a tubular part constricted with regard to the spheroidal part, the spheroidal part having a throat plate in its top 95 surface complementary to the cover slides.

Toronto, Ontario, October 28th, 1919.

JAMES ALEXANDER FLANAGAN.
